Specification for Design.

Patented Mar. 30, 1915.

Application filed October 21, 1914. Serial No. 867,911. Term of patent 7 years.

To all whom it may concern:

Be it known that I, JOHN H. KULOW, a citizen of the United States, residing at Buffalo, in the county of Erie and State of New York, have invented a new, original, and ornamental Design for a Combined Ink-Well, Pincushion, and Pen-Rack, of which the following is a specification, reference being had to the accompanying drawing, forming a part thereof.

Figure 1 is a perspective view of a combined ink well, pin cushion and pen rack, illustrating my new design. Fig. 2 is a perspective view of the same, looking from the rear.

What I claim is:

The ornamental design for a combined ink-well, pin-cushion, and pen-rack substantially as shown.

JOHN H. KULOW.
